UNITED STATES PATENT OFFICE.

ELLA D. SCHMITT, OF UPPER MONTCLAIR, NEW JERSEY.

PAN AND PLATE LIFTER.

1,137,536.

Specification of Letters Patent. Patented Apr. 27, 1915.

Application filed July 1, 1914. Serial No. 848,887.

To all whom it may concern:

Be it known that I, ELLA D. SCHMITT, a citizen of the United States, and a resident of Upper Montclair, in the county of Essex and State of New Jersey, have invented a new and Improved Pan and Plate Lifter, of which the following is a full, clear, and exact description.

My invention has for its object to provide a pan and plate lifter in two pieces, which are constructed of wire bent to obtain the greatest possible strength with the least weight. The construction permits the free movement of one of the pieces along the other for engaging the hooks on the pieces with a pan or plate or for disengaging them therefrom.

Additional objects of the invention will appear in the following specification in which the preferred form of my invention is disclosed.

In the drawings similar reference characters refer to similar parts in both the views in which—

25 Figure 1 is a plan view showing how my invention is used; and Fig. 2 is a side elevation of Fig. 1.

By referring to the drawings it will be seen that the lifter is constructed in two pieces 5 and 6, each of which is manufactured from a piece of wire. The piece 5 is looped at 7 and has parallel portions 8 spaced apart, these parallel portions 8 being bent at 9 and being twisted together at 10, by which means the terminal hooks 11 are strengthened. These terminal hooks 11 are bent so that they may be disposed under the rim 12 of a plate 13. The other wire member 6 is transversely disposed at 14 over the portions 8 of the wire member 5, the said other wire member 6 being bent downwardly at 15 at the outer sides of the portions 8 of the wire member 5. The wire

member 6 is then bent inwardly at 16 and longitudinally of the portions 8 of the wire 45 member 5 at 17, the wire member 6 then being bent up at 18 and outwardly over the portions 8 of the wire 15, terminals 19 of the said wire member 6 being bent down to form hooks for engaging the rim 12 of the plate 50 13 so that they may coöperate with the hooks 11 which have been described.

It will be understood that with this construction the lifter will be very light in weight while it will be sufficiently strong to 55 lift any necessary weight. The lifter is also of durable construction and may be manufactured at a trifling expense.

Having thus described my invention I claim as new and desire to secure by Letters 60 Patent:

In a device of the class described, a wire looped with its two parts disposed substantially parallel and spaced apart for a distance, the two parts of the wire being twisted together adjacent the terminals of the wire, the terminals of the wire being bent to form hooks, a second wire disposed transversely over the spaced apart portions of the first wire, the second wire being bent 65 down at the outer sides of the spaced apart portions of the first wire and then extending for a distance substantially parallel with each portion of the first wire in the direction of the hooks, the portions of the second 70 wire being then bent outward over the top of the said portions of the first wire and down to form hooks for coöperating with the first mentioned hooks.

In testimony whereof I have hereunto 80 signed my name to this specification in the presence of the undersigned witnesses.

ELLA D. SCHMITT.
